Patented Nov. 12, 1968

212,690

FIXED TELESCOPE SIGHT MOUNT FOR FIREARMS

Thomas Kuharsky, Jr., Erie, Pa., assignor to Bausch & Lomb Incorporated, Rochester, N.Y., a corporation of New York

Filed Mar. 26, 1968, Ser. No. 11,148

Term of patent 14 years
(Cl. D22—7)

FIG. 1 is a perspective view of a fixed telescope sight mount for firearms taken from the upper right-hand corner thereof; and

FIG. 2 is a perspective view of said mount for a fixed telescope taken from the bottom left-hand corner.

I claim:

The ornamental design for a fixed telescope sight mount for firearms, substantially as shown.
